UNITED STATES PATENT OFFICE

159,571

GAME BOARD

George O. Adams, Wilmington, Del.

Application August 5, 1948, Serial No. 147,949

Term of patent 14 years

(Cl. D34—5)

To all whom it may concern:

Be it known that I, George O. Adams, a citizen of the United States, residing at Wilmington, in the county of New Castle and State of Delaware, have invented a new, original, and ornamental Design for a Game Board, of which the following is a specification, reference being had to the accompanying drawing, forming part thereof.

The dominant features of my design reside in that portion shown in full lines in the drawing.

I claim:

The ornamental design for a game board, as shown and described.

GEORGE O. ADAMS,
